WORK-HOLDING CLAMP

Albert O. Mathison, Brooklyn, N. Y.

Application June 20, 1950, Serial No. 10,739

Term of patent 14 years

(Cl. D54—13)

To all whom it may concern:

Be it known that I, Albert O. Mathison, a citizen of the United States of America, residing at Brooklyn, in the county of Kings and State of New York, have invented a new, original, and ornamental Design for a Work Holding Clamp, of which the following is a specification, reference being had to the accompanying drawing, forming part thereof.

In the drawing:

Fig. 1 is a top plan view of a work holding clamp, showing my new design;

Fig. 2 is a front elevation view;

Fig. 3 is a bottom view;

Figs. 4 and 5 are, respectively, left and right side views of Fig. 1; and

Fig. 6 is a longitudinal sectional view taken along line 6—6 of Fig. 1 in the direction of the arrows.

I claim:

The ornamental design for a work holding clamp, substantially as shown.

ALBERT O. MATHISON.
